PRINTING-DIE STRUCTURE

Application filed July 13, 1928. Serial No. 292,387.

This invention relates to improvements in a die structure especially useful in mail-marking and check-endorsing machines and the like, and has for its principal object, the simplification and general improvement of such structures, as will be apparent from reading the following specification taken in connection with the annexed drawing, wherein:

Figure 1 is a plan view of a check endorsing machine of my design showing the application of my improved die thereto, the cover of the machine being thrown back, exposing the interior parts and the die plate being removed from the die structure.

Figure 2 is a part sectional view through the die structure.

Figure 3 is a view on the line 3—3 of Figure 2.

Figure 4 is a perspective view looking at the inner side of the die plate.

Referring now to the details wherein like numbers refer to corresponding parts in the various views:

1 is a framework of my check endorsing machine, within which is mounted a small electric motor 2 for the purpose of driving the mechanism. The motor 2 has a pinion 3, meshing with a gear 4, with which is associated a gear 5 that meshes with a gear 6, attached to a drive roller 7. One end of the drive roller 7 is especially constructed and engages with the clutch roller 48 comprising part of the die structure to be later described.

The check is fed to the drive roller 7 in the manner shown and described in my companion application, S. N. 292,386, filed July 13, 1928. On the opposite end of the machine from the position of the electric motor 2, a carrier frame 17 is mounted.

On the free ends of the carrier frame, which includes arms 18 and 19 on which the carrier frame is mounted in any suitable manner, is mounted a die structure 24. This die structure is generally of a construction similar to that shown in Jahn Patent 1,623,478, issued April 5, 1927, in which several groups of a series of type blocks 25 are adjustably mounted so that any die block of a series may be brought into printing position as determined by a die plate, not shown in Figure 1, on

which plate certain fixed indicia is usually cut or engraved.

My improvement with respect to this die structure resides particularly in the manner of locking and adjusting these series of die blocks, this improvement comprising; a pawl 27 for each group of die blocks, there being four of these pawls indicated in Figure 1. The pawls are so positioned as to have the nose thereof adapted to engage or enter between two of the die blocks, and when the die plate 26 is placed in position as shown in Figure 3, the pawls are securely held in locking position thereby.

To insure that the die plate 26 can normally be put on only in its proper position, it is provided with two projections 28 and 29, one of which is larger than the other, as shown in Figure 4. The larger one, 29, is adapted to enter a groove 30 in flange 31, at the end of the die, while the projection 28 is adapted to enter a corresponding groove 32 in the flange 33. The projections 28 and 29 are provided with notches to receive the finger 34 of a spring 35. From what has been said, it will be seen that the die plate may be quickly removed by pulling out the springs 35, at each end of the die, thereby disengaging the notches from the projections 28 and 29, releasing the die plate 26.

The die structure can be moved away from the drive roller in any suitable manner as by means of arms 36 and 37 which meet at a common point for co-action with suitable adjusting means not necessary to be described herein. After the die structure is moved away from the drive roller 7, the die plate 26 can be removed for the purpose of adjusting die block 25 to get suitable indicia for the check-stamping operation.

On one end of the shaft 44, of the die structure is slidably mounted by a key 45, a clutch element 46. The clutch element 46 engages within the clutch housing, a clutch plate 47 of any suitable material such as cork or composition thereof, which in turn engages a clutch roller 48 carried on a suitable bearing 89. The clutching effort is regulated by a spring 49, and adjusting nuts 50, and the surface of the clutch roller 48 is adapted to

engage the friction surface formed by the parts 9 and 10 of the drive roller 7, the rubber portion of this part of the drive roller being adapted to provide friction and the fabric portion to resist wear, and I have found that the combination of two such materials gives the best results in a machine of this character.

On the opposite end of the die structure from the drive roller 48 is carried a trip mechanism 51 generally of the same type as disclosed in Jahn Patent 856,345, issued June 11, 1907. The lever 52 of the trip mechanism is adapted to be engaged by the checks as they pass by the drive roller 7 and the die structure 24, thereby allowing the clutch structure through the medium of the clutch just described to turn the die structure and plate so the desired inscription may be stamped on the check as it passes between the drive roller and the die.

In order that the rest of the machine may be understood, it may be briefly stated that there is supported on the carrier frame an auxiliary frame having side plates 61 and 62. This auxiliary frame carries a felt roller 63, an ink roller 64, and a wiper roller 65. The felt or ink absorbent roller 63 has its bearing ends carried by a slot in each of the side plates 61 and 62, and is resiliently held in position by the springs 66 and 67, in engagement with the ink roller 64, which in turn is positioned so as to carry ink from the bottom of the auxiliary frame to the ink absorbent roller 63. The amount of ink which the ink roller 64 will carry to the roller 63 is regulated by the wiper roller 65, which latter roller has its ends positioned in grooves in the plates 61 and 62. The roller 65 is held in position in the groove 68 by means of a pair of roller bushings each having flanges 69 and 70 between which flanges, rests a spring, the tension of which can be adjusted by a screw, so as to give the desired pressure of the wiper roller 65 on the ink roller 64. A spring pawl and a ratchet on the ink roller 64 may be provided to prevent the ink roller from being turned in reverse direction, which would cause an unregulated amount of ink to be carried up onto the absorbent roller 63. The auxiliary frame is adjustable with respect to the die so as to get the proper pressure of the roller 63 on the die, by means of adjusting screws 75, and lock nuts 76, cooperating with their studs and slots 77. Adjusting studs 75 are carried on a back plate 78.

While I have described the application of my improved die to a check-endorsing machine, it will be clear that it may be used in other machines, for example, but not by way of limitation, in mail-marking machines.

Having thus described my invention, what I claim is:

1. A die structure particularly adapted for use in a check endorsing machine including;

a die having a plurality of a series of adjustable indicia blocks and a die plate having an aperture therein to fit around and expose the selected indicia, blocks of each series, means for locking each series of indicia in its selected position comprising pawls to drop between two blocks of a series, said pawls being held in place by the die plate.

2. A die structure particularly adapted for use in a check endorsing machine including; a die having a plurality of a series of adjustable indicia blocks and a die plate having an aperture therein to fit around and expose the selected indicia, blocks of each series, means for locking each series of indicia in its selected position comprising pawls to drop between two blocks of a series, said pawls being held in place by the die plate, a pair of flanges at each end of the die, each having a groove therein, the grooves differing in size, said die plate having projections to correspondingly fit said grooves and quick detachable means cooperating with said projections to lock the die plate in position on the die.

3. A die structure particularly adapted for use in a check indorsing machine, including; a die having a plurality of a series of adjustable indicia blocks and a die plate having an aperture therein to fit around and expose the selected indicia blocks of each series, means for locking each series of indicia in its selected position comprising pawls to drop between two blocks of a series, said pawls being held in place by the die plate, means provided whereby the die plate can be put on the die only in one way and quick detachable means for holding the die plate in position on the die.

4. A die structure particularly adapted for use in a check endorsing machine, including; a die having a plurality of a series of adjustable indicia blocks and a die plate having an aperture therein to fit around and expose the selected indicia blocks of each series, means for locking each series of indicia in its selected position, said die plate acting to hold said locking means in operative position, means for insuring that the die plate can be put onto the die only in the proper way and quick detachable means for holding the die plate in position on the die.

5. A die structure including a pair of laterally spaced flanges, a shaft extending through said flanges, a series of adjustable indicia blocks laterally spaced between said flanges, a die plate fitting over said blocks between said flanges and having an aperture therein to fit around and expose the selected indicia blocks of each series, pawls for locking each series of indicia blocks in its selected position, said pawls being held in locking position by the die plate, means cooperating between said flanges and the die plate to properly position the die plate, and means for

locking the die plate in said proper position.

6. A unitary die structure including; a pair of laterally spaced flanges, a shaft extending through said flanges and fastened thereto, a printing mechanism laterally spaced between said flanges, a die plate fitting over said printing mechanism between said flanges and having an aperture therein to fit around and expose the printing parts of said mechanism, means cooperating between said flanges and the die plate to properly position the die plate, means for locking the die plate in said proper position, a bearing on the shaft adjacent one of said flanges, a clutch roller carried by said bearing, said clutch roller having an overhanging rim, a clutch element fastened to said shaft inside said rim, and means on the shaft for adjusting the clutching effort between said roller and clutch element.

10 7. A unitary die structure particularly adapted for use in a check endorsing machine including; a die comprising a printing mechanism and a die plate having an aperture 15 therein to fit around and expose the printing parts of said mechanism, a shaft for supporting said previously mentioned parts, a bearing on the shaft, a clutch roller carried by said bearing, a clutch element secured on said shaft for cooperation with said roller, and means on the shaft for adjusting the cooperative effort between said roller and clutch element.

In testimony whereof, I affix my signature.
